J. L. Boren

UNITED STATES PATENT OFFICE.

FREDERICK B. SPOONER, OF BROOKLYN, NEW YORK.

SUSPENDER-END.

SPECIFICATION forming part of Letters Patent No. 372,820, dated November 8, 1887.

Application filed May 9, 1887. Serial No. 237,551. (No model.)

To all whom it may concern:

Be it known that I, FREDERICK B. SPOONER, a citizen of the United States, and a resident of Brooklyn, in the county of Kings and State 5 of New York, have invented certain new and useful Improvements in Suspender Ends or Attachments, of which the following is a specification.

My invention relates to suspender ends or 10 attachments, whereby the suspenders are secured to the buttons of pantaloons or other garments.

The object of the invention is to produce at small cost a device for the purpose stated, 15 which shall possess sufficient elasticity to compensate for the absence of rubber or other elastic means usually employed in the manufacture of suspenders, and which will enable the suspenders to readily adapt themselves to the 20 movements of the body of the wearer.

The invention is hereinafter described, and the claims at the end of this specification define the features of novelty for which protection is desired.

25 In the accompanying drawings, which form part of this specification, and in which like features are indicated by like letters of reference, Figure 1 is a front elevation of one embodiment of my invention. Fig. 2 is an elevation, 30 partly in perspective, of another embodiment of the invention; and Fig. 3 shows the manner of applying the attachment to the back of the suspenders.

Referring to the drawings, *a* indicates a 35 spring device, preferably of brass, and which is of sufficient strength and rigidity to take up any strain to which it might be subjected in the movements of the body of the person wearing suspenders to which this device is attached.

40 In Fig. 1 the letter *b* indicates the suspender, which is looped through the spring device *a*, and secured thereto by the slide *c*, of the usual construction. In this figure (1) the spring device *a* has its depending arms *d* provided with 45 housings *e*, preferably of the form shown, and adapted to receive the continuous cord, tape, or like device, *f*, in manner illustrated in said figure. The ends of said continuous cord are provided with means, *g*, for securing the same 50 to garments. The loops or housings *e*, Fig. 1,

are made of sheet metal or other suitable material and secured to the arms *d* by any desirable method, preferably a hinged connection.

In Fig. 3, *h i* indicate the suspender-straps at the point where they are connected at the 55 back. In this view, *k* indicates a metallic loop or ring, which may be more or less elongated, to which the suspender straps may be secured or through which they are passed for adjustment.

The spring device *a* in Fig. 2 is connected to the loop *k* by a ring, *l*, which may also be more or less elongated. By this arrangement a metallic hinged joint is effected between the suspender-straps and the spring device *a*, 65 thereby preventing the destruction of the straps by the rubbing action to which they might be subjected if attached directly to said spring device. The loop *l* serves the further function of strengthening the spring device *a* 7c at its upper horizontal bend, thereby enabling the employment of lighter wire in the construction of said spring device than could otherwise be the case. Of course, if desired, the loops *k l* may be dispensed with and the suspender secured directly to the spring device *a*, 75 as shown in Fig. 1.

The spring device *a* will be formed in any desirable shape best calculated to give good results, and its arms *d* will preferably be 80 turned at an angle to the body of the device, as shown.

In some instances it may be found desirable to employ pulleys, sheaves, or rollers *n*, secured within the housings, loops, or eyes of the arms 85 *d* of the spring device. These rollers may be of any suitable shape, and may be combined with the spring-arms by various means.

The continuous cord, tape, or analogous flexible device, *f*, operates the same in the several constructions. When a pull is exerted upon the continuous cord or the like, the spring device *a* not only yields by reason of its inherent elasticity, but there is a slight lengthening or elongation of the attachment, 95 due to the movement of the ends of the arms *d* of said spring device *a* toward the vertical axis of the attachment; and at the same time, during the approach of said arms *d* toward each other, that portion of the cord *f* which is 100

between said arms is shortened and the slack taken up, producing a considerable lengthening of the entire structure.

My attachment affords a yielding resistance at all times, and it readily accommodates itself to any position that the body of the wearer may assume.

By pivoting the sheet-metal loops to the arms *d* of the spring device, whereby said loops are adapted to swing laterally on the arms, I provide greater freedom of movement than could be obtained if the connection between the loops and arms were a rigid one.

I am aware that spring devices have heretofore been employed for connecting suspender-ends to the webbing; but I do not claim such feature, broadly.

Having thus described my invention, what I claim as new, and desire to secure by Letters 20 Patent, is—

1. The spring device for suspenders, comprising flexible arms and means, substantially as described, for connecting the suspender-

web, in combination with sheet-metal loops pivoted to the extremities of said arms and 25 adapted to swing laterally thereon, and a continuous cord having buttoning means at its ends and passing through and co-operating with both of said pivoted loops, substantially as set forth.

2. A suspender-end with means, substantially as described, for securing the same to the suspender-web, and provided with spring-arms *d*, having at their ends sheet-metal loops provided with segmental tubes attached to the 35 arms, and a continuous cord having button-hole tabs adapted to render through the loops, substantially as and for the purpose set forth.

Signed at New York, in the county of New York and State of New York, this 16th day 40 of April, A. D. 1887.

FREDERICK B. SPOONER.
